UNITED STATES PATENT OFFICE.

MAX E. DRAHEIM AND CHARLES E. DEMING, OF BEAVER DAM, WISCONSIN.

PACKAGE TIE.

Application filed February 23, 1927. Serial No. 170,281.

This invention aims to provide a simple means whereby a cord of any desired size, used for tying up a package of letters, or anything else, may be gripped firmly, to hold 5 the package, it being possible to release the cord readily at the will of an operator.

Another object of the invention is to provide an article of the class specified which will be simple in construction, not likely to 10 get out of order, and capable of being turned out in quantities, at trifling expense.

It is within the province of the disclosure to improve generally and to enhance the 15 utility of devices of that type to which the invention appertains.

With the above and other objects in view which will appear as the description proceeds, the invention resides in the combination and arrangement of parts and in the details of construction herinafter described 20 and claimed, it being understood that changes in the precise embodiment of the invention herein disclosed, may be made within in the scope of what is claimed, without departing from the spirit of the invention.

In the drawings:

Figure 1 shows in perspective, a bundle which has been bound with the device which forms the subject matter of this application;

Figure 2 is a sectional view which shows the parts as they will appear when the cord is gripped;

Figure 3 is a sectional view showing the parts as they will appear when the cord is not gripped;

Figure 4 is a section taken on the line 4—4 of Figure 3;

Figure 5 is a composite perspective view showing sundry parts of the gripping mechanism.

Saving for the flexible element or cord 18, hereinafter referred to, the device forming the subject matter of this application preferably is made of metal and includes a disk-like body 1, which, in cross section, is lens-shaped, as shown in Figure 4, the general construction of the body 1 being such that it will not mar any package on which it is placed. The body 1 has a cross hole 2 located near to its edge, and in the edge of the body 1 there is a reduced bore 3 which communicates with the cross hole. The flexible element 18 has a knot or other enlargement at one end, lodged in the hole 2,

the flexible element extending out through 55 the bore 3, as shown in Figures 2 and 3.

In the edge of the body 1 there is a chamber 4 communicating with a conical passage 5 that opens through the edge of the body 1 at a point opposite to the chamber 4. 60

The device includes a gripper which, as a whole, is marked by the numeral 6. The parts of the gripper 6 are shown in perspective in Figure 5, and it will there (and elsewhere) appear that the gripper includes a block-like head 7 provided with a threaded opening 8 which extends entirely through the head, as Figure 2 shows. The head 7 has ribs 9 on its sides, and these enable the opening 8 to be made of considerable 70 diameter, without using too much material in the making of the head 7.

The gripper 6 comprises tapered jaws 10 that are threaded at 11 for engagement in the threaded opening 8 of the head 7. The 75 jaws 10 are loosely threaded into the opening 8, so that they can swing a little, toward and away from each other, thereby to grip and release the cord 18. Not much motion is required to do this. The threads at 80 11 make a strong connection between the jaws 10 and the head 7, and no other pivot element is required, in order that the jaws 10 may swing toward and away from each other.

The head 7 of the gripper 6 slides in the chamber 4 of the body 1, and the tapered jaws 10 slide in the conical passage 5 of the body 1; and the construction is such, obviously, that the jaws and the body may be said to have relatively inclined cooperating parts which close the jaws toward each other when the jaws are moved longitudinally in one direction. The opening 8 in the head 7 serves not only to receive the threaded ends 90 11 of the jaws 10, but also admits the end of the cord 18 which is not secured by means of the nut or enlargement 19 to the body 1. The free end of the cord 18 extends along longitudinal grooves 12 which are formed in 95 the inner surfaces of the jaws 10. One jaw has a transverse rib 14 adapted to cooperate with an oppositely disposed transverse notch or seat 15 in the other jaw; and the last mentioned jaw has its own transverse rib 16 which cooperates with a transverse seat or notch 17 in the jaw which has the rib 14. Here note that the grooves 12 extend across 100 105

the ribs 16 and 14, as shown in Figures 5 and 2, the cord thus being held in place on the inner surfaces of the ribs 16 and 14.

The cord 18 is placed in any desired way 5 around a package 20 of letters, or anything else which is to be tied securely. When a pull is exerted on the end 21 of the cord, in the direction of the arrow A in Figure 1, the gripper 6 slides into the position shown 10 in Figure 3, and the operator can tighten the cord 18 as much as he pleases. When the free end 21 of the cord is released, the tension in the cord moves the gripper 6 into the position shown in Figure 2, the jaws 10 15 moving in the conical passage 5 of the body 1, and closing together tightly, to grip and hold the cord. Because the jaws 10 have the ribs 14 and 16, the cord is kinked as it is gripped (Figure 2) and is held with correspondingly increased strength; but a pull 20 on the end 21 in the direction of the arrow A will move the jaws 10 to the released position of Figure 3, and permit the cord 18 to pass through them.

25 What is claimed is:—

1. In a device of the class described, a body, a head slidable in the body, the head having an opening, and jaws loosely threaded into the opening for transverse swinging 30 movement, the jaws and the body having relatively inclined cooperating parts which close the jaws when the jaws are moved longitudinally in one direction.

2. In a device of the class described, a 35 body, a head slidable in the body, and jaws connected to the head for transverse swinging movement, the jaws and the body having relatively inclined cooperating parts which

close the jaws when the jaws are moved longitudinally in one direction, the jaws being 40 provided on their inner surfaces with transverse ribs which cooperate to kink and hold a flexible element.

3. In a device of the class described, a body, a head slidable in the body, and jaws 45 connected to the head for transverse swinging movement, the jaws and the body having relatively inclined cooperating parts which close the jaws when the jaws are moved longitudinally in one direction, the jaws being 50 supplied on their inner surfaces with means for kinking a flexible element, said means comprising a transverse rib on one jaw, the inner surfaces of the jaws having longitudinal grooves for the reception of a flexible 55 element, and one of the grooves extending across the rib.

4. In a device of the class described, a body, a head slidable in the body, and jaws 60 connected to the head for transverse swinging movement, the jaws and the body having relatively inclined cooperating parts which close the jaws when the jaws are moved longitudinally in one direction, the jaws being 65 provided on their inner surfaces with transverse ribs which are disposed out of registration longitudinally of the jaws, each jaw having a seat for the reception of the rib of the other jaw, the jaws being 70 equipped upon their inner surfaces with longitudinal grooves that extend across the ribs.

In testimony that we claim the foregoing as our own, we have hereto affixed our signatures.

MAX E. DRAHEIM.
CHARLES E. DEMING.
